(57) **CLAIM**

What is claimed is the ornamental design for a chisel, as shown and described.

DESCRIPTION

FIG. 1 is front elevation view of the chisel, the rear elevation view being a mirror image thereof.

FIG. 2 is a perspective view of the chisel of FIG. 1.

FIG. 3 is a top view of the chisel of FIG. 1; and,

FIG. 4 is a bottom view of the chisel of FIG. 1.

The dashed lines are shown for environmental purposes only and form no part of the claimed design.

1 Claim, 2 Drawing Sheets
